UNITED STATES PATENT OFFICE.

JAMES S. TAYLOR, OF NEWBURGH, NEW YORK.

DESIGN FOR A DIRECTORY.

42,596.

Specification for Design.

Patented June 4, 1912.

Application filed November 15, 1911. Serial No. 660,532. Term of patent 3½ years.

To all whom it may concern:

Be it known that I, JAMES S. TAYLOR, a citizen of the United States, and residing at Newburgh, New York, have invented a new, original, and ornamental Design for a Directory, of which the following is a specification, reference being had to the accompanying drawing, forming a part thereof.

The figure is a perspective view of a directory showing my new design.

I claim:
The ornamental design for a directory, as shown.

JAMES S. TAYLOR.

Witnesses:
JOHN SMITH,
PH. FARLEY.
